DEVICE FOR LIFTING GOLF BALLS

John E. Borah, 815 Mishawaka Ave., Mishawaka, Ind.

Filed Oct. 9, 1961, Ser. No. 67,012

Term of patent 14 years

(Cl. D34—5)

FIGURE 1 is a perspective view of a device for lifting golf balls, showing my new design. The broken line showings of a ball and golf club handle portion are for illustrative purposes only.

FIGURE 2 is a top plan view of the device shown in FIGURE 1;

FIGURE 3 is a side elevational view of the present device;

FIGURE 4 is a bottom view of the device; and

FIGURE 5 is a vertical cross sectional view of the device taken on line 5—5 of FIGURE 2.

I claim:

The ornamental design for a device for lifting golf balls, substantially as shown and described.
